(57) **CLAIM**

The ornamental design for a belt system, as shown and described.

DESCRIPTION

FIG. 1 is a top, front exploded perspective view of a belt system in accordance with our new design;

FIG. 2 is a bottom, rear perspective view thereof;

FIG. 3 is a front view thereof;

FIG. 4 is a rear view thereof;

FIG. 5 is a left view thereof;

FIG. 6 is a right view thereof;

FIG. 7 is a top view thereof;

FIG. 8 is a bottom view thereof;

FIG. 9 is a top, front perspective view of the belt system in an open position in accordance with our new design;

FIG. 10 is a bottom, rear perspective view thereof;

FIG. 11 is a front view thereof;

FIG. 12 is a rear view thereof;

FIG. 13 is a left view thereof;

FIG. 14 is a right view thereof;

FIG. 15 is a top view thereof;

FIG. 16 is a bottom view thereof;

FIG. 17 is a top, front perspective view of the belt system in a closed position in accordance with our new design;

FIG. 18 is bottom, rear perspective view thereof;

FIG. 19 is a front view thereof;

FIG. 20 is a rear view thereof;

FIG. 21 is a left view thereof;

FIG. 22 is a right view thereof;

FIG. 23 is a top view thereof, and,

FIG. 24 is a bottom view thereof.

The claim to a belt system is directed to the collective appearance of the two belts shown in the drawings. The broken lines in the figures illustrate stitching and form part of the claimed invention. The break lines symbolize breaks in length of the article in which the claimed design is

(Continued)

embodied. The appearance of any portion of the article between the break lines forms no part of the claimed design.

1 Claim, 16 Drawing Sheets
